A. W. SCHMUTZER

JUMPER

Filed Oct. 17, 1925

Fig. 1.

Fig. 2.

UNITED STATES PATENT OFFICE.

ANTON W. SCHMUTZER, OF CRANDON, WISCONSIN.

JUMPER.

Application filed October 17, 1925. Serial No. 63,072.

To all whom it may concern:

Be it known that I, ANTON W. SCHMUTZER, a citizen of the United States, and resident of Crandon, in the county of Forest 5 and State of Wisconsin, have invented certain new and useful Improvements in Jumpers; and I do hereby declare that the following is a full, clear, and exact description thereof.

10 The invention relates to jumpers for children, such devices being commonly known as teeter-totters.

15 Objects of this invention are to provide a device which will support a child and permit the child to readily operate the device, to raise and lower the child in a periodic manner, and to provide a device which is freely portable and does not occupy a great amount of room.

20 Further objects are to provide a device of the above type which is equipped with resilient restoring means adapted to balance the weight of the child and is so constructed that the tension of the resilient means will be exactly proportioned to the weight of the child in a simple and easy manner.

An embodiment of the invention is shown in the accompanying drawing, in which:—

25 Figure 1 is a side elevation of the device, such view being partly in section.

Figure 2 is a rear view of the structure shown in Figure 1.

30 Referring to the drawings, it will be seen that the device is provided with a bed plate or platform 1 which may be provided with 35 rollers or sliding knobs 2 in any suitable manner. This platform carries uprights 3 which are preferably of channel iron and are securely braced by means of the strap members or braces 4 extending downwardly and rearwardly from the uprights and secured at opposite ends of the uprights and base.

35 The oscillating or pivotally mounted beam 5 is provided with a transverse metal member 6 equipped with downwardly turned apertured ears 7. A supporting rod or pintle 8 extends through the uprights 3 and through the ears 7. The beam or rocking bar 5 is provided with a seat portion 9 at its outer end and is provided with a triangular framework consisting of a piece of strap iron having a flat portion 10 secured to the under side of the bar and having a vertical portion 11 joined to a diagonal or slanting portion 12,

55 The lower ends of the portions 11 and 12 are joined by an eye bolt 13. A spring 14 has one end hooked in the eye bolt 15 adapted to be received in any one of the apertures 16 in the base 1. The outer end of the spring is provided with a hook 17 adapted to be hooked into the eye bolt 15, as shown, or any one of the apertures 18 formed in the diagonal arm or member 12.

60 It is intended that the forward end of the rocking beam 15 be ornamented with an animal head or suitable device such as indicated at 19, and if desired, reins 20 may extend rearwardly from such head.

65 In order to accommodate children of different weights, the adjustment for the spring 70 is provided as previously described. This adjustment may be made in a very accurate manner by either varying the length of the lever arm from the beam 5 by passing the hook 17 of the spring through any of the 75 apertures 18 or through the eye bolt 13. Further, if additional tension is needed, the bolt 15 may be inserted in a more remote aperture 16.

80 It will be seen that a device has been provided which is readily adjusted to the exact weight of the child and that a free and easy motion of the device is permitted.

85 Although the invention has been described in considerable detail, it is to be understood that the invention may be variously embodied and is, therefore, to be limited only as claimed.

I claim:

1. A device of the class described comprising a base having a plurality of apertures adjacent its rear end, uprights carried by said base adjacent its forward end, a beam pivoted between said uprights and having a downwardly extending arm, said arm being of triangular construction, a spring having its forward end secured to said arm, and a bolt attached to the rearward end of said spring and adapted for insertion into anyone of the apertures in said base.

90 2. A device of the class described comprising a base having a plurality of apertures adjacent its rear end, a plurality of uprights projecting from said base adjacent its forward end, a beam pivoted between said forward uprights and having a seat formed at its outer end, a strap-like member secured to said beam and bent to form a downwardly

projecting triangular arm, an eye bolt joining the ends of said strap, a portion of said strap being provided with a plurality of apertures, a spring having a bolt at its rear end adapted for insertion in any one of the apertures in said base and having a hook at its forward end adapted for engagement

with said eye bolt or with any of the apertures in said strap.

In testimony that I claim the foregoing ¹⁰ I have hereunto set my hand at Crandon, in the county of Forest and State of Wisconsin.

ANTON W. SCHMUTZER.
